ABSTRACT

Electrodes for an electric discharge lamp, such as a "rapid start" fluorescent lamp, comprise a plurality of elongated filaments in close parallel mutual adjacency, preferably touching one another. This reduces the thermal inertia of the electrodes and results in faster filament heating and quicker lamp starting, greater current capacity, and longer life.

MULTIPLE-FILAMENT ELECTRODES FOR ELECTRIC DISCHARGE LAMPS

The present application is a continuation in part of my copending application Ser. No. 345,535 filed Mar. 28, 1973, now abandoned.

BACKGROUND OF THE INVENTION

The invention is in the field of electric discharge lamps, such as fluorescent lamps, and is more particularly directed to filament-type electrodes for use in such lamps of the "rapid start" type which are started by simultaneously applying operating voltage across the electrodes and heating current through the filaments of both electrodes.

Fluorescent lamps generally comprise a pair of electrodes respectively sealed into the ends of an elongated glass envelope which contains a combination of gases at suitable pressure for causing an electric discharge when voltage is applied across the electrodes. Each of the lamp electrodes comprises one or more elongated filaments carried by a lead-in wire arrangement. The filaments are coated with suitable electron emission materials so as to function as cathodes, i.e., a source of electrons for current flow in the lamp. The lamp electrodes may also be provided with anode elements, or in some cases, the cathodes may also function as anodes to receive the discharge electron flow on alternate half-cycles of a-c electrical energy.

The required area of the electron-emitting cathodes is a function of desired current in the electrical discharge in the lamp. For twice as much discharge current, approximately twice as much cathode area is required. For a single cathode, typically comprising an elongated coiled or coiled-coil filament, to double the surface area (without increasing the length) requires quadrupling the cross-section area, and hence weight, of the filament wire. This considerably increases the thermal mass of the cathode and hence undesirably increases the time required for the cathode to reach proper electron-emitting temperature when a "rapid start" lamp is started. This slower heating of the cathode results in damage to the cathode at each starting, particularly in "rapid start" lamps, because of the discharge starting due to voltage field effect and "tearing" away electrons and also emission material from the cathode before the cathode has reached proper electron-emitting temperature. This reduces the cathode life. Electrodes provided with multiple cathodes help reduce this undesired effect, since the multiple cathodes increase the total cathode electron-emitting area without increasing the thermal mass as much as in the case of a single-filament cathode. U.S. Pat. Nos. 2,337,993 to Hall and Le Gette and 3,448,318 to Campbell and Kershaw disclose multiple filaments arranged in spaced parallelism in a crisscross configuration and in a straight line configuration.

SUMMARY OF THE INVENTION

Electrodes for an electric discharge lamp, such as a "rapid start" fluorescent lamp, comprise a plurality of elongated filaments in close parallel mutual adjacency, preferably touching one another. This reduces the thermal inertia of the electrodes and results in faster starting, greater current capacity, and longer life. The arrangement also increases the amount of electron-emitting material that can be coated onto, and held by, the filaments.

BRIEF DESCRIPTION OF THE DRAWING

FIG. 1 is a side view of a fluorescent lamp constructed in accordance with a preferred embodiment of the invention, interior construction details being shown in dashed lines;

FIG. 2 is a perspective view of one of the two identical electrodes used in the lamp of FIG. 1; and

FIG. 3 is a top view of the electrode of FIG. 2 in a modified form with adjacent filament coils touching one another.

DESCRIPTION OF THE PREFERRED EMBODIMENTS

The lamp shown in FIG. 1 comprises an elongated tubular glass bulb 11 having a coating of phosphor material 12 on the inner surface thereof. A pair of electrodes 13, 14 are sealed at the ends of the bulb, respectively, in well-known manner. Each of the electrodes 13, 14 comprises a filament or cathode means 16 attached at the ends thereof to in-lead support wires 17a and 17b which are sealed through glass stems 18 and are electrically connected to connector pins 21 and 22 carried by base cap arrangements 23 and 24 respectively attached to the two ends of the bulb 11. The bulb 11 may contain mercury and argon or other suitable fill material for sustaining an electric discharge between the electrodes 13 and 14.

As shown in FIG. 2, each of the electrode assemblies 30 13 and 14 comprises a pair of lead-in support wires 17a and 17b sealed through a glass stem 18, as has been described above. An exhaust tubulation 19 is shown, for use in evacuating air from the bulb 11 and applying suitable fill gas or gases into the bulb during manufacture of the lamp, after which the tubulation 19 is sealed off. A plurality of elongated filaments 26, 27, 28, which may be of the coiled, coiled-coil, or other suitable type of filament, are positioned in close parallel adjacency, preferably with mutually adjacent filaments touching 35 one another at a plurality of places, and lying in a plane substantially parallel to the flare 29 of the stem 18, and are held in place by the lead wires 17a and 17b being bent to crimp into and against the filaments 26, 27, and 28 near the ends thereof, as shown. More specifically, 40 and as shown in FIG. 2, each of the support wires 17a and 17b is shaped to provide a U-shaped segment positioned so that the legs thereof extend along the row of filaments respectively above and below and in clamping engagement with all of the filaments, the two U-shaped clamping segments being respectively near the ends of the row of filaments. If desired, the ends of the lead wires 17a and 17b, after being formed to crimp and hold the filaments 26, 27, and 28, may be extended and shaped to form anode electrodes, as indicated by numerals 31 and 32. After the filaments 26, 27, and 28 are attached to the lead-in wires 17a and 17b, they are dipped into an electron emission mixture, which may be of any well-known composition and which dries to 45 form a continuous unitary electron-emitting coating 33 over and around all of the filaments.

To achieve the objectives of the invention, the spacing between mutually adjacent filaments should be no greater than the diameter of each of the filaments. Normally, all of the filaments will have the same diameter and will be identical in other respects so that when heating current is applied to them the current will be 50 equally distributed among the parallel-connected fila-

ments. If for some reason mutually adjacent filaments are employed which have differing diameters, they should be no farther apart than the diameter of the smaller diameter filament.

In the preferred embodiment of FIG. 3, the filaments are close together so that mutually adjacent filaments 26, 27 and 27, 28 touch one another at a plurality of places along the lengths thereof.

When the electrode arrangement of the invention, as shown in FIG. 2, is employed in an electric discharge lamp, and especially in a fluorescent lamp of the "pre-heat" or "rapid start" type of lamp in which heating current is fed through the filaments, it is found that the group of filaments will heat up to proper electron-emitting operating temperature much faster than prior art electrode structures to support a given arc current, because the close adjacency of the filaments to one another causes the heating of each of them to help heat one or more of the other filaments. This faster heating of the filaments to proper selectron-emitting temperature permits faster starting of the "preheat" type of lamp and results in longer life in a "rapid start" type of lamp in which operating electron-emitting is applied across the electrodes 13 and 14 simultaneously with application of heating current to the filaments of each of the electrodes. By thus reducing the thermal mass of the filament arrangement by utilizing several filaments, and providing faster warm-up due to the close adjacency of the multiple filaments, there is less time during each start-up of the lamp in which the electric field intensity between the electrodes in the lamp can "tear" or "pull" away electrons, and also emission material, from the cathode or filaments before they have reached proper electron-emitting temperature. Also, the close parallel adjacency of the multiple filaments increases the amount of electron-emitting material that can be coated onto, and held by, the cathode structure. Also, the close adjacency causes the cathode-emitting area to be shared proportionally among the several cathodes, thus resulting in a unitary electron-emitting configuration.

While preferred embodiments of the invention have been shown and described, various other embodiments

and modifications thereof will become apparent to persons skilled in the art and will fall within the scope of the invention as defined in the following claims.

What I claim as new and desire to secure by letters patent of the United States is:

1. An electrode for an electric discharge lamp, comprising at least three helically coiled elongated electrical filaments arranged side by side in a row lying in a plane, the mutually adjacent ones of said filaments being positioned in close parallel mutual adjacency, the spacing between mutually adjacent filaments being no greater than the diameter of either of them, electron-emitting material coated on said filaments, and a pair of lead-in electrical conductors respectively at the ends of the plurality of filaments and connecting them in electrical parallel.
2. An electrode as claimed in claim 1 in which mutually adjacent filaments of said electrode touch one another at a plurality of places along the lengths thereof.
3. An electrode as claimed in claim 1 in which said electron-emitting material is coated over said plurality of filaments and forms a continuous unitary coating over and around all of the filaments.
4. An electrode as claimed in claim 1 including a stem and a pair of lead-in support wires extending from said stem, each of said wires being shaped to provide a U-shaped segment, one of said U-shaped segments being positioned so that the legs thereof extend along said row respectively above and below and in clamping engagement with all of said filaments near the ends thereof at one side of said row, and the other one of said U-shaped segments being similarly positioned in clamping engagement with all of said filaments near the other ends thereof at the other side of said row, whereby said U-shaped segments simultaneously support and provide electrical connections to said plurality of filaments.

5. An electrode as claimed in claim 4 in which at least one of said legs of the U-shaped segments extends from said clamping engagement with the filaments and into space near the filaments so as to function as an anode member of said electrode.
